UNITED STATES PATENT OFFICE.

WILLIAM JOHN VINCENT, OF CARDIFF, ENGLAND, ASSIGNOR TO THE ROTOPLUNGE
PUMP COMPANY, LIMITED, OF CARDIFF, WALES, ENGLAND.

CHANGE-SPEED AND REVERSING GEARING.

1,007,756.

Specification of Letters Patent.

Patented Nov. 7, 1911.

Application filed March 11, 1911. Serial No. 613,837.

To all whom it may concern:

Be it known that I, WILLIAM JOHN VINCENT, a subject of the King of Great Britain, residing at Albert Chambers, High street, 5 Cardiff, Wales, England, have invented new and useful Improvements in Change-Speed and Reversing Gearing, of which the following is a specification.

This invention relates to a certain combination of a hydraulic clutch with reversing epicyclic gearing for the purpose of obtaining an infinite number of speeds in either direction. The hydraulic clutch consists as is usual of a rotary pump delivering liquid to its own suction through a regulating valve. According to this invention the driving shaft is connected to one of the members of the pump and also has fixed to it one of the elements of the epicyclic train, 15 the other elements of which are respectively carried by the driven shaft and the other member of the pump. The hydraulic clutch it is preferred to employ is that described in the specification of the U. S. Patent No. 25 980,368.

Figure 1 is a longitudinal section of an apparatus constructed according to this invention. Figs. 2, 3 and 4 are sections on the lines 2—2, 3—3, and 4—4, Fig. 1, and 30 Fig. 5 shows a detail.

1 is the driving shaft which has keyed to it the block 2 and the pinion 3. The block 2 revolves in contact at one point with the casing 4 and has a number of radial cylinders 35 5 formed in it. These cylinders contain pistons 6 carrying pins 7 the ends of which lie in eccentric grooves 8 in the sides of the casing 4 so that as the shaft 1 and block 2 revolve clockwise relatively to the casing 4 40 the pistons are moved in and out and liquid is forced through the valve 9 in the direction of the arrow. By closing the valve 9 more or less the flow of liquid is throttled and the casing 4 is carried around with the 45 shaft 1 at a speed depending on the amount of throttling. Hydraulic clutches of this type are well known and no further description is therefore necessary. The casing 4 is extended on one side to contain the epicyclic 50 gearing hereinafter described.

10 is the driven shaft which is recessed to receive the end of the driving shaft 1. The end of the driven shaft 10 is square and carries the pinion 11 which can be moved to 55 and fro along it by the fork 12 carried by

the pin 13 fixed to the sleeve 14 which can be moved to and fro by the arms 15 on the rocking shaft 16.

The epicyclic train is as follows:—The pinion 3 on the shaft 1 is always in gear with the pinion 17 on the shaft 18 which is free to revolve in bearings in the casing 4 and has also fixed to it the pinion 19. The shaft 18 is cut away in the section Fig. 1 but is shown separately at Fig. 5. The pinion 19 is always in gear with a pinion 20 fixed on the shaft 21 free to revolve in bearings in the casing 4 and having also fixed to it the pinion 22. The sliding pinion 11 on the driven shaft 10 can be put into gear either 70 with the pinion 19 on the shaft 18 or with the pinion 22 on the shaft 21 or it can be left between and out of gear with them. 23 is a brake strap around the casing 4. With this arrangement there are four positions in 75 which the shaft 1 does not drive the shaft 10. A. Assume that all the parts are in the positions shown, the valve 9 being fully open as shown in Fig. 1, the brake 23 being slack and the pinions 3—17, 19—11 and 19—20 all 80 in gear. Then the shaft 1 and pinion 3 revolve clockwise, the case 4 of the pump and gear box revolve backward from the pinion 3. The shaft 10 is stationary as its resistance is more than that of the case so that 85 the pinion 17 walks backward around the pinion 3 and the pinion 19 walks backward around the pinion 11 and as (in the arrangement shown) the reduction of gears through 3—17, 19—11, is two to one, it follows that 90 the case revolves backward at half the speed of the shaft 1 while the shaft 10 remains stationary. B. Next slide the pinion 11 out of mesh with 19 and then the case becomes 95 stationary and is quite a free member while the pinions 3—17, 19, 20—22 all revolve. Now since there is no contact with the pinion 11 there is no movement of the case, except the frictional movement caused by the revolving shaft 1. C. If the clutch valve 9 100 be now closed, the case 4 will revolve locked to the shaft 1 by the compressed liquid in the clutch but will only act as a fly wheel and do no useful work. D. Lastly. Open the clutch valve 9. Slide the pinion 11 into 105 mesh with the pinion 22. This causes the case 4 to revolve with the shaft 1, but at a reduced speed, according to reduction in speed through the pinions 3—17, 19, 20—22 meshing into the pinion 11.

When the parts are in the position A above, the shaft 10 can be driven by two methods. If the brake 23 be applied the case is brought to a standstill. Thus the motion of the shaft 1 is conveyed positively through the gears to the pinion 11 thereby revolving the shaft 10 in the same direction as the shaft 1, but at a reduced speed. This gives a low speed and the case becomes a stationary gear box. The brake 23 could be eased off a little and this would allow the case to revolve backward and give a slower speed. Or instead of putting on the brake 23 the valve 9 may be gradually closed; this compresses the liquid against the valve and causes the case to come from the backward motion into a forward motion. When the valve is fully closed it locks the whole together, therefore no pinions revolve relatively to the case but the whole revolves as one unit including the shaft 11. If the valve is allowed to open a little, liquid escapes past it and the speed of the case is slower than that of the shaft 1 and therefore the pinions revolve relatively to the case. Thus an infinite variety of speeds can be obtained, the more the valve is opened the greater the difference between the speed of the shaft 1 and case 4.

When the parts are in the positions B and C above, the shaft 11 cannot be driven but when they are in the position D it can be driven either backward or forward. If the brake 23 be applied the case is brought to a standstill and there is a positive drive through the reduction gears which revolves shaft 10 backward, that is the reverse. This speed can be regulated by slipping the brake a little or much. If the brake 23 be released and the clutch valve 9 be closed, the case is locked to the shaft 1; and therefore locks all the pinions, and the shaft 10 is revolved in same direction as the shaft 1 thus giving a forward drive which can be varied by opening the valve more or less.

It will thus be seen that the direction of rotation of the shaft 11 can be changed from reverse to forward or forward to reverse without shifting the gears, the brake 50 gives the reverse and the valve the forward motion.

What I claim is:—

1. The combination of a pump having communicating suction and delivery passages and comprising a drum and a casing surrounding it, a valve between the suction and delivery passages, an epicyclic train,

the middle element of which is carried by the casing, a driving shaft connected to the drum and to one of the end elements of the 60 epicyclic train, a driven shaft connected to the other end element of the epicyclic train, and a brake acting on the casing.

2. The combination of a pump having communicating suction and delivery passages, a valve between the suction and delivery passages, a reversing epicyclic train, a driving shaft connected to one member of the pump and to one element of the epicyclic train, a driven shaft connected to another 70 element of the epicyclic train, and a brake acting on the third element of the epicyclic train such element being connected to the other member of the pump.

3. The combination of a pump having 75 communicating suction and delivery passages and comprising a drum and a casing surrounding it, a valve between the suction and delivery passages, a reversing epicyclic train, the middle element of which is carried by the casing, a driving shaft connected to the drum and to one of the end elements of the epicyclic train, a driven shaft connected to the other end element of the 80 epicyclic train, and a brake acting on the 85 casing.

4. The combination of a pump having communicating suction and delivery passages, a valve between the suction and delivery passages, an epicyclic train having 90 reversing mechanism, a driving shaft connected to one member of the pump and to one element of the epicyclic train, a driven shaft connected to another element of the epicyclic train, a brake acting on the third 95 element of the epicyclic train such element being connected to the other member of the pump.

5. The combination of a pump having 100 communicating suction and delivery passages and comprising a drum and a casing surrounding it, a valve between the suction and delivery passages, an epicyclic train having reversing mechanism, the middle element of which train is carried by the casing, a driving shaft connected to the drum and to one of the end elements of the epicyclic 105 train, a driven shaft connected to the other end element of the epicyclic train, a brake acting on the casing.
